UNITED STATES PATENT OFFICE.

WALTER S. SHOURDS, OF PHILADELPHIA, PENNSYLVANIA.

CONCRETE CONSTRUCTION.

No. 858,227.

Specification of Letters Patent.

Patented June 25, 1907.

Application filed May 31, 1906. Serial No. 319,611.

To all whom it may concern:

Be it known that I, WALTER S. SHOURDS, a citizen of the United States, residing in Philadelphia, Pennsylvania, have invented certain Improvements in Concrete Construction, of which the following is a specification.

The object of my invention is to make a substantial and comparatively cheap building construction of concrete, dispensing with the cumbersome thick blocks, or with wooden or steel uprights or studs. This object I attain by making the studs of concrete, preferably reinforced, and attaching to these studs the facing slabs of concrete which are also preferably reinforced.

In the accompanying drawings: Figure 1, is a perspective view illustrating a portion of a stud made in accordance with my invention; Fig. 2, is a vertical sectional view on the line 2—2, Fig. 3, without the concrete filling; Fig. 3, is a sectional plan view on the line 3—3, Fig. 2; Fig. 4, is a perspective view of one of the concrete studs; Fig. 5, is a face view of one of the studs; Fig. 6, is a view of a corner stud; Fig. 7, is a view of the stud in which the chimney opening is formed; Fig. 8, is a view showing the metallic reinforce of the slabs extending into the groove in the stud; Fig. 9, is a view showing another form of corner stud; Figs. 10 and 11, are views of beams which may be formed in the same manner as a stud; Fig. 12, is a sectional plan view of a modification illustrating a partition stud; and Fig. 13, is a view of a modification.

A, A are the studs arranged at any given distance apart, same as the wooden studs of a building, and B, B are slabs. These studs are made of concrete molded in any suitable manner with a groove *a* in one face as illustrated clearly in Fig. 4. The groove in this stud is preferably made V-shaped so as to form a pocket not only for a concrete filling but also for reinforcing rods *c*. Each stud is also preferably reinforced so that it can be readily handled after being molded. Rods *a'*, netting, or other reinforcing means may be used without departing from my invention. Lugs *a'* may be formed within the V-shaped groove *a* of the stud as clearly illustrated in Figs. 2 and 5, so that when the reinforcing rod *c* is placed in position there will be a space back of the rod so that it will be entirely embedded in cement. In some instances I secure a furring strip *D* to the stud. This strip may be embedded in the concrete or may be secured to it by nails which are

previously driven in the furring strip and embedded in the concrete while still in a plastic state so as to overlap and attach the furring strip to the stud, or means may be provided for attaching the furring strip to the stud after it has been molded and set.

Fig. 6, shows a corner stud *A'* having the groove in the corner instead of at the side so as to secure the two sets of slabs which are arranged at an angle to each other. The slabs are secured to the inside of the stud in this instance but they may be secured to the outside as shown in Fig. 9. In this modification, the furring strip is at one side of the corner while in Fig. 6, it is at the corner.

In Fig. 7, I have shown my improved stud shaped so as to form a chimney opening *a'*, and Fig. 8 illustrates the method I prefer to use whenever possible, turning in the reinforcing rods *b* of the slabs *B* so that they will be embedded in the cement *i* which ties the slabs to the stud.

In Fig. 10, I have shown the stud laid horizontally instead of vertically, utilized as a beam, and in Fig. 11 I have shown another form; the opening *a* in the beam being of such a width that two longitudinal stay rods can be placed in the groove instead of one. The shape of the groove will depend entirely upon the character of the work for which the stud is intended.

In constructing a building in accordance with my invention, I place the studs in a vertical position and then place the slabs against the studs securing them together by cement, the slabs being arranged so that some of the joints will come in line with the grooves of the studs as shown in Figs. 1 and 3. The cement or concrete filling is then poured into the grooves of the studs, some of the cement entering the space between the ends of the slabs, when the material is set, it will form a positive union between the studs and slabs.

In some instances, as shown in Fig. 8, where an extra tie is desired, I may bend the metallic reinforce of the slabs *B* at right angles so that they will enter the groove *a* and when the concrete filling is poured into the groove and set they will be embedded in the cement. As illustrated in Fig. 3, the stud may have any number of reinforcing rods extending longitudinally through it to give it strength, and one or more heavier rods may be placed in the groove *a* according to the type of structure to be built, and while my invention is particularly adapted for the ver-

tical studs of a building; it can be used also as a beam, as illustrated clearly in Figs. 10 and 11.

Where the stud is to support an iron frame-work, it is preferably grooved at the end as shown in Fig. 4, the groove being T-shaped, so that a T-beam can rest in the groove.

It will be understood that the stud can be shaped to fit any form desired, depending upon the character of the building.

I claim:

1. The combination of an integral stud of concrete having a longitudinal groove in one face, with slabs of concrete resting against said face, and secured thereto by concrete filling in the groove, substantially as described.
2. The combination in an integral concrete stud having a groove in one face, slabs of concrete mounted against said face, the slabs having their abutting edges in line with the groove, with a filling mounted in the groove and uniting the slabs to the stud, substantially as described.
3. The combination of a stud having a longitudinal groove in one face, slabs mounted against said face, the ends of the slabs bearing against the face, and overlapping the groove, and spaced apart with cement poured into the groove while in a fluid state, and uniting the slabs to the stud, the said cement filling the space between the ends of the slabs, substantially as described.
4. The combination of a stud having a groove in one face thereof, slabs resting

against the grooved face of the stud, a reinforcing rod mounted within the groove, and cement in the groove embedding the tie rod and uniting the slabs to the stud, substantially as described.

5. The combination of a stud having a groove in one face thereof, slabs resting against the said face of the stud, reinforcing rods in the said stud, and a reinforcing rod in the groove of the stud, cement poured into the groove while in a fluid state, the cement embedding the rod and uniting the slabs to the stud, and uniting the end of one slab to the other, substantially as described.

6. The combination of a concrete stud having a groove in its face, reinforced slabs secured to the grooved face of the stud by cement poured into the groove while in a fluid state, the reinforcing members of the slabs being turned into the groove, substantially as described.

7. As a new article of manufacture, a concrete stud having a groove in one face thereof, lugs projecting into the groove and so arranged that a tie rod placed in the groove will be held away from the back of the groove so that it will be embedded in cement placed in the groove, substantially as described.

In testimony whereof, I have signed my name to this specification, in the presence of two subscribing witnesses.

WALTER S. SHOURDS.
